UNITED STATES PATENT OFFICE.

GEORGE H. WILLARD, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed July 28, 1925. Serial No. 46,534.

To all whom it may concern:

Be it known that I, GEORGE H. WILLARD, a citizen of the United States, and a resident of Hopedale, in the county of Worcester and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms and more particularly to the intermittent type of such mechanisms wherein the feeler has periods of activity and periods of inactivity during weaving with the same supply of filling in the shuttle.

In feeler mechanisms of the intermittent type it is desirable that the feeler shall be held in an inoperative position beyond the reach of the filling on detecting beats during periods of inactivity of the feeler. This inoperative position of the feeler during its periods of inactivity may be accomplished in various ways, as by moving the feeler frontwardly beyond the reach of the filling on detecting beats, or by moving the feeler laterally when it is pushed frontwardly by a working supply of filling in the shuttle. In accordance with the present invention, the feeler is moved laterally to an inoperative position beyond the reach of the filling on detecting beats, and in order to prevent accidental movement of the feeler back to its original lateral position, means are provided for locking the feeler from lateral movement when it has been moved to its inoperative position.

In feeler mechanisms of the intermittent type, so called, it is frequently desirable to vary the periods of inactivity in accordance with the character of the filling in use. For instance, if the filling be of large count or coarse yarn, it will be depleted from the shuttle more rapidly than when the filling is of finer count, and consequently, in the use of coarser yarn, the periods of inactivity of the feeler should be relatively short, whereas, in the use of the finer count yarns the inoperative periods of the feeler may be relatively long. In accordance with another feature of the invention, therefore, means are provided for varying the periods of inactivity of the feeler in accordance with the character of the yarn in use.

The invention, new combination of parts and novel features thereof will best be made clear from the following description and the accompanying drawings of one good, practical form of the invention.

In the drawings:

Fig. 1 is a plan view of a feeler mechanism, some of the parts being broken away, embodying the present invention;

Fig. 2 is a side view showing more particularly the step-by-step member and the trip device for varying the periods of inactivity of the feeler;

Fig. 3 is a perspective view of a feeler mechanism embodying the present invention, showing the step-by-step member for operating the trip device actuated from the cam follower;

Fig. 4 is a detached detail showing more particularly the step-by-step member and the changeable relation of the trip device in its connection therewith;

Fig. 5 is a detailed perspective view with parts broken away showing more particularly the detent and locking device associated with the feeler, the parts being in disengaged relation; and

Fig. 6 is a cross-sectional detail showing the detent and the lock engaged with the feeler to prevent lateral movement of the feeler in either direction when in its inoperative position.

Feeler mechanisms are now usually employed for changing the operative condition of the loom when the filling in the shuttle reaches substantial exhaustion, and in the present instance of the invention, the feeler mechanism is shown as associated with filling replenishing mechanism for replenishing the filling when substantial exhaustion of the filling has been reached. The details of the replenishing mechanism form no essential part of the present invention and are therefore not shown, since they are now well understood in the art.

Having reference more particularly to Fig. 3, the loom frame 1 may be of usual construction, and rising from the usual transverse shaft which extends to the replenishing side of the loom, as usual, is the arm 2 having pivotally connected thereto at 3 the actuator 4 the rear end portion of which has pivoted thereto at 5 the lever 6, the rear end portion 7 of which is adapted

at times to be engaged by the cam follower 8 or a part connected thereto. Pivotally mounted at 9 on the support 10 secured to the loom frame is a bell crank lever, the 5 horizontal arm 11 of which underlies the finger 12 carried by the lever 6, and connected to the arm 13 of the bell crank lever is the transmitter 14, the opposite end portion of which is connected at 15 to a slide 16 mounted in suitable guideways at the rear portion of the feeler stand 17, the construction being such that should the slide 16 be moved laterally to the left, Fig. 3, the rear end portion of the lever 6 will be placed in 10 the path of the operating member 8 and replenishment of filling will be initiated.

Extending through an opening in the slide 16 is the feeler 18, the forwardly extending end portion 19 of which passes 20 through the swivel bearing 20 mounted between the bracket 21 and the feeler stand.

The feeler 18 is provided with a bridge or support 22, the end portions of which rest upon the top surface of the feeler stand, 25 and interposed between the bridge 22 and the front bearing 20 is a spring 23 normally acting to move the feeler into its rearward feeling position. The feeler stand 17 may be adjustably secured to the shipper stand 30 or a bracket carried thereby through the medium of a bolt 24 which passes through a slot 25 in the feeler stand. The feeler 18, in the present instance of the invention, is shown as of the inclined type, that is, it is 35 mounted upon the feeler stand to enter the shuttle in a direction inclined to the longitudinal axis thereof, and the rear end portion of the feeler is provided with one or more teeth 26 adapted to engage the filling 40 in the shuttle on a detecting beat.

The shuttle 27 is provided with the usual bobbin holding jaws 28 for holding the bobbin or filling carrier 29 on which the filling 30 is wound. The parts so far described may be substantially the same as the similar parts described and shown in the patent to Edward S. Stimpson, No. 1,309,223, July 8, 1919, to which reference may be had for a more full disclosure of the details.

50 In accordance with the present invention, the feeler is to be held in a forward inoperative position beyond the reach of the filling on detecting beats, and, as shown, this characteristic inoperative position of the feeler during its periods of inactivity is produced by the lateral movement of the feeler when the latter has been moved forwardly by a working supply of filling in the shuttle and the lay goes back.

60 In the present instance of the invention, the feeler is provided with the tooth 31, the rear surface 32 of which is inclined laterally relative to the forward holding surface 33 of the detent 34, the effect being that when the feeler has been moved forward by a

working supply of filling on a detecting beat and the lay goes back, the relatively inclined surfaces of the detent and feeler engaging portions will act under the impulse of the spring 23 to move the feeler laterally from dotted to full line position, Fig. 1, where it will be held by the detent during its periods of inactivity beyond the reach of the filling on detecting beats. 70

The detent 34 is pivotally mounted at 75 35 preferably upon a lug 36 extending upwardly from the feeler stand, and the front end portion of the detent 34 is normally under the influence of a light spring 37 tending to lift the front end portion of the detent, as indicated in Figs. 2 and 3. Since the normal position of the detent under the action of the spring 37 maintains its rear end portion 38 in lowered position, it is desirable that the rear end surface 39 of the detent be 80 vertically inclined to cooperate with the inclined surfaces 40 on the front portion of the feeler tooth 31, the effect being that when the feeler is moved forwardly by a working supply of filling on a detecting beat, the inclined surfaces 39, 40 will cause the feeler to lift the detent and permit the detent to drop into engagement with the relatively and laterally inclined surfaces 32 carried by the feeler lug, and as the lay goes 85 back and such relatively inclined surfaces are forced into engagement by the spring 23, the feeler will be moved laterally as indicated in Fig. 1, so that its rear toothed portion 26 will be beyond the reach of the filling on detecting beats. 90

In accordance with one feature of the present invention, the feeler is to be locked from lateral movement in either direction when in its inoperative position, as above 105 described, and while various forms of locks may be utilized for preventing such lateral movement of the feeler in either direction during its periods of inactivity, the preferred form of the suggested lock is such as shown more particularly in Figs. 5 and 6, wherein the tooth 31 carried by the feeler is provided with a locking portion 41 which is adapted to be engaged by the cooperating locking member 42 carried by the rear portion of the detent 34. The lock as shown is formed with the locking member 42 of the detent of the general wedge shape shown, while the cooperating locking portion of the feeler is formed by a substantially correspondingly shaped recess, the construction being such that when the feeler has been moved forwardly by a working supply of filling on a detecting beat and the tooth 31 of the feeler has engaged the tooth of the detent as the lay goes back, the feeler will be moved laterally, and coincident with this lateral movement, the locking members will engage and thereafter hold the feeler from lateral movement in either direction until 110

the feeler is subsequently released from the 5 detent to its period of activity. The effect of the locking feature is manifest during weaving and serves to maintain the feeler in its lateral inoperative position, as indicated in Fig. 1, without danger of recurring contact with the filling by the return of the feeler laterally to its original or initial position.

10 In accordance with the present invention, the feeler is to be tripped at intervals to its periods of activity, and a trip device is provided whereby the periods of inactivity of the feeler may change in accordance with 15 the character of the filling in use.

As shown in the present instance, the 20 feeler stand has extending therefrom a stud or dead shaft 43 on which is rotatively mounted the step-by-step member 44, herein shown as a wheel provided with teeth 45 and having a hub portion 46 through which the stud or dead shaft 43 extends. Mounted on the angular hub portion 46 of the toothed wheel is the trip device 47 which may be 25 secured to the hub 46 by suitable means, such as the screw 48, the result being that the trip device 47 rotates with the toothed wheel 44.

The trip device 47 is provided in the 30 present instance with two trip portions, the main trip portion 49 which is shown has a wide tooth extending substantially the longitudinal length of the hub portion of the trip device, and the auxiliary trip portion 50 of less 35 width than the main trip portion 49, for a purpose as will presently appear.

Extending from the detent 34 is a lug 51 which projects laterally from the detent, as indicated in Figs. 1 and 3.

40 When fine count yarn is being used in the loom as filling, it is desirable that the periods of inactivity of the feeler shall be longer than when coarser yarn is employed, and to thus vary the tripping action of the trip device, the trip is connected with the toothed wheel for relative change of position to effect one or the other of these purposes. When relatively long periods of inactivity of the feeler are desired, the trip device 47 will be connected to the toothed wheel with the auxiliary trip portion 50 adjacent the surface of the toothed wheel 44, as indicated in Fig. 1, whereupon the main trip portion 49 alone of the trip device will act upon the projection 51 of the 50 detent to free the feeler on each rotation of the toothed wheel. On the other hand, should a different count of yarn be used in the loom and shorter periods of inactivity of the 60 feeler be desired, the trip device 47 will be shifted or changed in its relation to the toothed wheel to place the auxiliary trip portion 50 in position to also act upon the projection 51 extending from the detent, whereupon on each half revolution of the

toothed wheel, the trip device will act to trip the feeler or free it to its periods of activity.

The connection between the trip device and the toothed wheel may be variously contrived, but a good, practical, convenient 70 form of such connection is shown in Fig. 4 wherein the hub portion 46 of the toothed wheel is angular in cross-section and two of its edges at 52 and 53 are bevelled or cut away to correspond to a similarly shoul- 75 dered portion 54 in the hub of the trip device 47, the effect being that the trip device may be secured to the toothed wheel in its proper relation thereto to secure either long or short periods of activity of 80 the feeler.

It is sometimes desirable that the step-by-step movement of the toothed wheel 44 may not be too free, or such as to overrun, and as one means of retarding the too free rotation of the toothed wheel, the present invention provides a spring 55, Fig. 1, mounted upon the stud or dead shaft 43 and interposed between the fixed casing 56 and the surface of the toothed wheel 44, as indicated 90 in Fig. 1, and while the spring 55 affords the proper retarding action to the too free movement of the toothed wheel, other equivalent means may be employed for this purpose. 95

In accordance with the present invention, the toothed wheel 44 is to be given a step-by-step movement and this may be effected from any going part of the loom. In the present instance, however, such step-by-step movement of the toothed wheel is effected from the cam follower. Mounted in suitable bearings 57, 58 formed in a bracket 59 secured to the loom frame or shipper stand, as by the bolt 60, is the rock shaft 61, the outer end portion 62 of which has secured thereto a clamp 63 to which is pivotally connected at 64 the pawl 65, the construction being such that upon rocking movement of the rock shaft 61, the pawl 65 will actuate the toothed wheel 44 step-by-step to thereby operate the trip device. The shaft 61 has secured thereto at its inner end 66 a crank arm 67, the bifurcated end portion 68 of which engages a pin 69 mounted on the cam follower 70 or a part operated thereby. The cam follower 70 is mounted for rocking movement upon the support 71 and its lower end portion 72 carries a shoe 73 which rests upon the cam 74 on a constantly rotating 105 shaft 75, the effect being that as the cam follower is given its usual movement, the rock shaft 61 will be rocked and the pawl 65 effect a step-by-step movement of the toothed wheel and the trip device 47 connected thereto. 110

It may be desirable in some instances to provide a limiting stop for the pawl 65 in its idle stroke, and in the present instance this is afforded by a pin 76 projecting from 120

the fixed casing 56, so that as the pawl partakes of its idle stroke and disengages itself from the teeth of the wheel 44, it will rest upon the pin 76 and be ready for its active stroke.

While the details of the present invention may be varied within the true scope thereof, the described details form a practical and efficient means for locking the feeler in its 10 inoperative position from lateral movement during its periods of inactivity, and the selected connection of the trip device with the step-by-step member affords a good practical means for varying the periods of inactivity of the feeler in accordance with the character of the yarn in use.

What is claimed is:

1. In a feeler mechanism for looms, the combination of a feeler, a feeler holding 20 detent for holding the feeler in a frontward position, means for causing the feeler to swing laterally into an inoperative position beyond the reach of the filling where it is held by the detent during its periods of inactivity, a lock for holding the feeler from lateral movement in either direction during its periods of inactivity, and means of freeing the feeler from the detent and lock at intervals.

2. In a feeler mechanism for looms, the combination of a feeler, a feeler holding 30 detent for holding the feeler in a frontward position, means for causing the feeler to swing laterally into an inoperative position beyond the reach of the filling where it is held by the detent during its periods of inactivity, a lock for holding the feeler from lateral movement in either direction during its periods of inactivity, and means actuated 40 from the cam follower for freeing the feeler from the detent and lock at intervals.

3. In a feeler mechanism for looms, the combination of a feeler, a feeler holding 45 detent for holding the feeler in a frontward position, means for causing the feeler to swing laterally into an inoperative position beyond the reach of the filling where it is held by the detent during its periods of inactivity, locking members, one on the feeler 50 and the other on the detent for holding the feeler from lateral movement in either direction during its periods of inactivity, and means for freeing the feeler from the detent and lock at intervals.

4. In a feeler mechanism for looms, the combination of a feeler, a spring normally 55 acting to move the feeler rearwardly, means for moving the feeler laterally to an inoperative position as the lay goes back with a 60 working supply of filling in the shuttle, a detent lock for holding the feeler in frontward inoperative position, a locking projection and recess, one on the detent and the other on the feeler for locking the feeler 65 from movement laterally in either direction

during its periods of inactivity, and means for freeing the feeler from the detent and lock at intervals.

5. In a feeler mechanism for looms, the combination of a feeler having periods of 70 activity and inactivity during weaving with the same supply of filling in the shuttle, a detent for holding the feeler in an inoperative position during its periods of inactivity, means for moving the feeler laterally to a 75 position beyond the reach of the filling on detecting beats that it may be held in such position by the detent during periods of inactivity, a lock for holding the feeler from lateral movement in either direction during 80 its periods of inactivity and means for freeing the feeler from the detent and lock at intervals.

6. In a feeler mechanism for looms, the combination of a feeler, a detent for holding 85 the feeler in a frontward inoperative position, a projection carried by the feeler to engage the detent when the feeler is moved frontwardly by a working supply of filling in the shuttle, means for causing the feeler to move laterally into an inoperative position beyond the reach of the filling, a lock for securing the feeler from lateral 90 movement in either direction from said inoperative position during periods of inactivity, and means for freeing the feeler at 95 intervals.

7. In a feeler mechanism for looms, the combination of a feeler, a detent for holding 100 the feeler in a frontward inoperative position, a projection carried by the feeler to engage the detent when the feeler is moved frontwardly by a working supply of filling in the shuttle, means for causing the feeler to move laterally into an inoperative position beyond the reach of the filling, a lock for securing the feeler from lateral 105 movement in either direction from said inoperative position during periods of inactivity, and means actuated from the cam follower 110 for freeing the feeler at intervals.

8. In a feeler mechanism for looms, the combination of a feeler, a detent for holding 115 the feeler in a frontward inoperative position during periods of inactivity, a device for tipping the detent to free the feeler at intervals, comprising two tripping members constructed and arranged to selectively permit both of said tripping members to trip the detent for relatively short periods of inactivity of the feeler and one only of said members to trip the detent for relatively longer periods of inactivity of the feeler.

9. In a feeler mechanism for looms, the combination of a feeler, a detent for holding 125 the feeler in an inoperative position during periods of inactivity, a trip device for freeing the feeler at intervals having a main trip and an auxiliary trip, and means for changing the position of the trip device to cause 130

the main trip and auxiliary trip to be effective for relatively short periods of feeler inactivity and the auxiliary trip to be ineffective for relatively longer periods of 5 feeler inactivity.

10. In a feeler mechanism for looms, the combination of a feeler, a detent for holding the feeler in a frontward inoperative position during periods of inactivity, a device 10 for tripping the detent to free the feeler at intervals, comprising two tripping members constructed and arranged to selectively permit both of said tripping members to trip the detent for relatively short periods of 15 inactivity of the feeler and one only of said members to trip the detent for relatively longer periods of inactivity of the feeler, and means actuated from the cam follower for operating the trip device.
20. 11. In a feeler mechanism for looms, the combination of a feeler, a detent for holding the feeler in an inoperative position during periods of inactivity, a step-by-step member actuated from a going part of the loom, a 25 trip device having a main trip portion and

an auxiliary trip portion, and means for changeably connecting the trip device to the step-by-step member to cause both of said trip portions to act upon the detent and free the feeler from the detent when relatively short periods of inactivity of the feeler are desired and to cause only one of said trip portions to act upon the detent when relatively longer periods of inactivity are desired. 30

12. In a feeler mechanism for looms, the combination of a feeler, a detent for holding the feeler in an inoperative position during periods of inactivity, a trip device having a main and an auxiliary trip portion, and 40 means for changing the position of the trip device relative to the detent to cause one of said trip portions to act in freeing the feeler for relatively long periods of inactivity and both of said portions to act to free the feeler 45 for relatively shorter periods of inactivity.

In testimony whereof, I have signed my name to this specification.

GEORGE H. WILLARD.
